Primary Examiner — Mary Ann Calabrese*(74) Attorney, Agent, or Firm* — QuickPatents; Kevin Prince**(57) CLAIM**

I claim the ornamental design for an illuminated address panel, as shown and described.

DESCRIPTION

FIG. 1 is a perspective view of an illuminated address panel, showing my new design;
FIG. 2 is an exploded perspective view thereof;
FIG. 3 is a front elevational view thereof;
FIG. 4 is a rear elevational view thereof;
FIG. 5 is a left-side elevational view thereof, the right-side elevational view being a mirror image thereof; and,
FIG. 6 is a top plan view thereof, the bottom plan view being a mirror image thereof.

The broken lines showing an address sheet in FIGS. 1 and 2 and mounting hardware in FIG. 3 depict environmental matter and form no part of the claimed design. The areas between the break lines in the figures depicting no specific width form no part of the claimed design.
